UNITED STATES PATENT OFFICE.

JAMES Y. HENRY, OF PHILADELPHIA, PENNSYLVANIA.

GAME.

964,644.

Specification of Letters Patent. Patented July 19, 1910.

Application filed October 19, 1909. Serial No. 523,490.

To all whom it may concern:

Be it known that I, JAMES Y. HENRY, a citizen of the United States, residing at Philadelphia, in the county of Philadelphia 5 and State of Pennsylvania, have invented certain new and useful Improvements in Games, of which the following is a specification.

My invention relates to an improved game, 10 and more particularly to an improved game board, which is ruled or printed in an improved manner providing a field divided by heavy and light lines, into squares or spaces, and providing in said spaces, representations, indicating forts, located in improved 15 positions on the fields:

A further object is to provide an improved game in which the board is especially adapted for playing a game wherein forts 20 are represented upon the board or field of the board and are to be captured by suitable men or pieces moved about the field.

With these and other objects in view the invention consists in certain novel features 25 of construction and combinations and arrangements of parts as will be more fully hereinafter described and pointed out in the claims.

In the accompanying drawings, Figure 1, 30 is a plan view of my improved game board; and Fig. 2, is a view illustrating one style of men, or pieces which may be used in connection with my improved board.

My improved board is preferably of rect- 35 angular form, of greater length than breadth, and provided all around its edge with a heavy line or border 1, forming a field, which is divided by longitudinal and transverse lines 2 and 3, arranged an equal 40 distance apart, all of said longitudinal lines being parallel, as well as all of said transverse lines, so as to sub-divide the field into a plurality of rectangular spaces 4. The field is further divided by means of two 45 heavy transverse lines 5 and 6, said lines located appreciably nearer the ends of the board than the center of the board so that the central field will be appreciably larger than the end fields, said lines being prefer- 50 ably marked "Dead line". In the spaces adjacent the end lines of the board, and located in alternate spaces, are representations 55 of forts 7, which are open at one end; that is the open ends facing toward the center of the field. These spaces are preferably

marked with the word "Fort" and with numerals beginning with the numeral 1, and increasing in regular numeric ratio from 1 to 5, five of said forts being shown at each end of the board. In the central space or 60 field 8, forts are also located, and are arranged substantially as shown. These forts being also open at one end and contain the word "Fort", and are marked with different numerals, one of said forts having the 65 character 1, and the others, characters increasing in numeric value. Four of these forts are located nearer one end of the board, while the other four are located nearer the opposite end of the board, all of said forts 70 have their open ends toward the center of the board and the combined numeric value of the forts at one side of the center is precisely like the combined numeric value of the forts at the other side of the center. 75

This board is adapted for playing games, more particularly representative of war, wherein, men or pieces are employed representing soldiers, which are to be moved by opponents, at opposite ends of the board, in 80 an endeavor to capture the forts represented on the board.

In Fig. 2, I have shown one form of men or pieces which may be utilized. That is each player would be provided with one 85 man, such as shown at 8, which would represent a general. One man, such as shown at 10, which would represent a captain, and a plurality of men as shown at 11, which could represent common soldiers or privates. 90 But of course other forms of men or pieces might be utilized.

In playing the game, each player starts with a general, a captain, and a number of men indicated in Fig. 2, and places them in 95 any of the squares at his end of the board in the space between the head line and the end of the board. Each player plays alternately and moves his men, one at a time, straight ahead or at right angles, and if one of his 100 men is in front of him, he may jump that man so as to more rapidly move his pieces toward the center of the field and toward the opponent's forts. But when a player gets his men in such position that three of 105 his men, with an officer behind them, are in line with the open end of one of the enemy's forts, he may move a man into such fort and take possession, and as long as he retains a man in the fort, the numeric value 110

of the fort belongs to him. After the opponent gets four of his men in line with an officer at the rear, in line with the open end of this same fort, he will recapture his own fort, and if he has a man standing in front of the fort, it cannot be captured unless the opponent has four men in line and an officer. The game is usually played by providing a bag or sack containing a number of 5 balls, which are marked with different numerals, and each player draws a ball and puts it in his pocket, so that his opponent does not know what number he has drawn, then each player tries to capture the forts 10 of the opponent in the manner above stated, and when he has captured enough of the enemy's forts, the numeric value of which combined with the value of the ball he has drawn totals 30, he is the winner. His 15 opponent not knowing the numeric value of the ball he has drawn, is confused as to the campaign his opponent is mapping out, and as his total must be exactly 30, it gives to each player an opportunity to finesse and 20 deceive his opponent as to just which forts he wants. The first player capturing the 25 forts, which combined with the ball he has drawn exactly totals 30, is the winner. In moving the men, it is preferable that the 30 ordinary man be permitted but a single move, unless a man is in front of him to jump over, while the captain is allowed a move of four spaces in either direction, and the general a move of any number of spaces 35 in either direction, but the minor rules of the game may be varied without departing from the invention.

These representations of forts may be 40 captured in various ways, but preferably by jumping the men one over the other, but I do not limit my invention to any particular way of playing the game, nor to any particular construction of pieces or men for playing the game, but consider myself at

liberty to utilize my improved board for 45 any purpose to which it may be adapted.

Having thus described my invention what I claim as new and desire to secure by Letters Patent is:—

1. A game apparatus consisting of a board 50 or field divided by longitudinal and transverse lines into a plurality of spaces, transverse heavy lines dividing said plurality of spaces into three fields, representations of forts in the alternate spaces at both ends of 55 the board or field, representations of forts in the center field, an equal number of representations of forts being provided on both sides of the center field, and each of said representations of forts having one open side, 60 the open side of every representation of a fort being toward the center of the board, and pieces adapted to be moved on the said spaces, substantially as set forth.

2. A game apparatus, consisting of a board 65 or field divided by longitudinal and transverse lines into a plurality of spaces, transverse heavy lines under the caption dead line dividing said spaces into three fields, a series of representations of forts in the 70 spaces as shown and described, all of said representations of forts having one open side open toward the center of the board, each of said representations of forts under the caption "Forts" and each representation of a fort marked with a numeral, and men representing officers and soldiers adapted to be moved about said board to capture 75 said representations of forts, substantially as set forth.

In testimony whereof I have signed my name to this specification in the presence of two subscribing witnesses.

JAMES Y. HENRY.
